UNITED STATES PATENT OFFICE.

CHARLES MILLER, OF ST. LOUIS, MISSOURI.

LAMP.

Specification of Letters Patent No. 28,683, dated June 12, 1860.

To all whom it may concern:

Be it known that I, CHARLES MILLER, of the city of St. Louis, State of Missouri, have invented a new and Improved Lamp for the 5 Burning of Any Kind of Coal-Oil; and I do hereby declare that the following is a full and exact description thereof, reference being had to the accompanying drawings and to the letters of reference marked 10 thereon.

The nature of my invention consists in the interposition of two upright metallic regulators or wings (1) one on each side of the flame of an ordinary coal-oil lamp, which 15 regulators (1) by means of a thumb screw are made to impinge upon, partially cutting in two and dividing the flame. These regu-

lators are made of German silver, curved over at the top to meet the flame, with a width at the top equal to the wick to be 20 used. The lower portion of these regulators consist of a narrow strip of the same metal passing down along side of the tube containing the wick, and inserted into a cooler (3) or small chamber containing water. 25

What I claim as my invention and desire to secure by Letters Patent is—

The combination of a cooler with the regulators as herein described.

CHARLES MILLER.
